BOOTJACK

Robert L. Greer, Salem, Oreg.

Application November 1, 1954, Serial No. 32,880

Term of patent 14 years

(Cl. D7—2)

Fig. 2

Fig. 1 is a top perspective view of a bootjack showing my new design;

Fig. 2 is a bottom plan view of the bootjack, and
Fig. 3 is a side elevational view thereof.

I claim:

The ornamental design for a bootjack, as shown.
